CONNECTION FOR DOOR CLOSERS

Filed July 15, 1935

UNITED STATES PATENT OFFICE

2,110,889

CONNECTION FOR DOOR CLOSERS

Courtney N. Mitchell, Strongsville, Ohio

Application July 15, 1935, Serial No. 31,387

9 Claims. (Cl. 16—49)

The present invention, relating as indicated, to connections for door closers, is particularly directed to the provision of an arrangement whereby the door closer can be installed within a limited space such as ordinarily exists between the main door and the screen door or storm door in the usual residence installation. Heretofore door closers could be installed between doors only if the doors were spaced at considerable distance and then at a considerable sacrifice in the effective closing force exerted on the door due to the unfavorable direction of pull caused by the necessary proportions of the linkages employed. When there is insufficient space between the doors for the door closer and its linkages, the door closer must be installed on the outside of the building which exposes the device to weather conditions and possible loss by theft. This outside installation presents an unfavorable appearance and detracts from the harmony of the architectural scheme. The principal object of this invention is to obviate the above disadvantages by providing means of installing the door closer in a very limited space between doors. Another object is to provide means of securing a very effective pull on the door at the latching position. Another object is to provide a means of varying the pull on the door by changing the leverage as the door swings. Another object is to provide a means of adjusting the position of the door lever relative to the door. A still further object is to provide a means of connection for a door closer which is composed of inexpensive parts easily and cheaply assembled.

To the accomplishment of the foregoing and related ends, said invention, then, consists of the means hereinafter fully described and particularly pointed out in the claims. The annexed drawing and following description set forth in detail certain mechanism embodying the invention, such disclosed means constituting, however, but one of the various mechanical forms in which the principle of the invention may be used.

In the said annexed drawing Fig. 1 is a plan view of the door closer as installed between two doors and shows the door structure in section on the line 1—1 of Fig. 2. Fig. 2 is a side elevation of the door closer installation as seen from the position indicated by line 2—2 of Fig. 1. Fig. 3 is a section on line 3—3 of Fig. 1 showing the door attachment bracket on a somewhat enlarged scale.

The present invention is particularly adaptable to installations of light storm doors, screen doors and in other locations where only a limited space

is available and where it is necessary that the door to which the closer is attached be closed with a force which continually increases as the door swings toward the latching position. This invention has distinct advantages from the standpoint of neatness, inconspicuousness and harmony with surrounding architectural features. One of its chief advantages lies in the ease of assembling the door closer and its related parts to the door and the door casing and in the low cost of the parts required to make this assembly. This invention is particularly adaptable to a door closer of the type shown in my Patent No. 1,836,383, but is quite readily applicable to closers of other forms and constructions.

Referring now to the drawing, the door closer 5 is attached to the door casing 6 by means of screws 7 and bracket 8 which is secured permanently to the housing of the closer 5. The bracket 8 is sufficiently narrow and of such form as to require but limited space and extends very little beyond the diameter of the housing of the door closer. The main door 9 swings on hinge 10 and ordinarily is provided with another door closer located on the inside of the building and which is not shown on the drawing. The storm or screen door 11 turning on hinge 12 swings outwardly to the position shown in the broken lines at 13.

The lever 14, which is of channel form, is attached to the tapered and fluted shaft of the door closer 5 by means of screw 15. The bracket 16 is attached to the rail of the door by screws 17. This bracket carries adjusting plate 18 which is provided with an elongated opening 19 through which bolt 20 passes and which serves as a means of clamping plate 18 in adjusted position to bracket 16. The roller 21 is attached to the outer end of plate 18 by means of shoulder rivet 22, this rivet acting as a journal bearing 40 for the roller. A recessed head 23 of the rivet prevents the roller from becoming detached from the plate when it is removed from the channel of lever 14. The edges of the channel may be bent inwardly as shown at 24 if it is desired to maintain the roller and lever in definite relation to each other. In this case the roller is assembled into the channel by inserting it into the enlarged portion 25 adjacent the boss for the attachment screw 15.

The outer end of the channel shaped lever is provided with a semi-circular end 25 which serves as a stop for limiting the angular movement of the door, the roller engaging the inner surface of the curved flange end and preventing move-

ment beyond a position predetermined by the length of the lever and the position of the closer on the door casing. This limit of the door movement is a little beyond the position shown by the broken lines in Fig. 1.

As the torque exerted by the spring actuated shaft of the closer turns the lever 14 and closes the door, the roller 21 is caused to move along the channel of the lever toward the end attached 10 to the door closer. The length of the moment arm contacting with the closer is thus gradually reduced which more than compensates for the loss of torque in the door closer spring as it approaches the closed position. This moment arm 15 may be made smaller and the force exerted on the roller much larger at the closed position of the door by placing the bracket 16 nearer the hinge. Ordinarily the distance from the door closer to the roller is of the order of two and 20 one half inches when the door is closed and is seven to eight inches when the door is fully opened, thus giving a length ratio of open moment arm to closed moment arm of approximately three to one.

25 After the installations of the door closer and the door bracket have been made the adjusting plate 18 may be regulated by means of the slot provided therein and clamp bolt 20 so as to secure the correct position for the release of the hydraulic resistance within the closer for the engagement of the door latch as may be provided in the internal construction of the unit.

As may be noted from the drawing, the door lever as well as bracket 16 and plate 18 are made 35 from sheet metal which insures low cost of production of these parts as machine work is eliminated and the weight of the material required is very much reduced from that ordinarily needed for the production of such parts. The door lever 40 14 has a drawn boss 26, substantially in the form of a truncated cone which engages the tapered and fluted shaft of the door closer and which provides for any easy means of making the major or coarse adjustment, the adjustment provided 45 by the slotted opening in plate 18 being the minor or fine adjustment.

For the purpose of avoiding the slipping of plate 18 on bracket 16 when the roller 21 engages the end 25 of the door lever in the full open position of the door, the plate 18 is provided with 50 a contacting surface having fine sharp flutes and is hardened to provide a substantially positive engagement with the bracket 16 which is made of soft steel. In some cases, the plate 18 is 55 omitted and the bracket 16 is extended to provide place for the attachment of the roller 21 directly to its outer end. Suitable washers or shims for adjustment may then be used between the bracket and the door 11.

60 In order to conceal the door lever 14 and bracket 16 and to improve the general appearance of the device when the door is open, a sheet metal cover may be provided of the form substantially as indicated by the broken lines at 27. This 65 cover may be finished to harmonize with the color and general appearance of the door to which the device is attached.

Other modes of applying the principle of my invention may be employed instead of the one 70 explained, change being made as regards the mechanism herein disclosed, provided the means stated by any of the following claims or the equivalent of such stated means be employed.

I therefore point out and distinctly claim as 75 my invention:

1. In a connection for a door and a door closer, a channel shaped arm having an end portion attached to the door closer, and a roller adapted to engage said channel shaped arm, said roller being carried by a plate, and the said plate being 5 adjustably secured to a bracket carried by the door.

2. In a connection for a door and a door closer, an arm having an opening to receive a shaft of the door closer, a channel in said arm to receive 10 a member attached to the door, the said channel having a closed end to limit movement of said member, and means for adjusting the position of said member relative to said door whereby said arm is brought into substantially parallel relationship with said door when the door is in closed position.

3. In a connection for a door and a door closer, an arm having attachment to the door closer, a door member having attachment to the door and 20 constrained to move along said arm, the attachment to the door comprising a bracket secured to the door and a connecting member secured to said bracket, the said connecting member being adjustable relative to said bracket whereby when the 25 door is closed, the arm is substantially parallel with but spaced from said door.

4. In a connection of the character described, an operating member having a shaft energized to operate in one direction, a lever secured to said 30 shaft and adapted to be moved thereby, an element adapted to move radially in the lever, the said element being attached to an operated member, and means for adjusting the element relative to the operated member whereby a change in a 35 force exerted by the operating member on the operated member is effected.

5. In a connection for a door and door closer, a lever secured to the door closer and adapted to be moved thereby, an element adapted to move 40 radially along said lever, the said element being attached to a door, and means for adjusting the element relative to the door whereby a force applied to said door is changed as the said door approaches a closed position.

6. In a connection for a door and a door closer, an arm having an inner end portion attached to the door closer, a member constrained to move longitudinally along said arm, a support for said member having an attachment on said door, said attachment being so located on said door that the said member is adjacent to the inner end of the arm when the door is closed and is adjacent to an outer end of the arm when the door is open.

7. In a connection for a door and a door closer, 55 an arm having an inner end portion attached to the door closer, a member constrained to move along said arm, a support for said member having an attachment on said door, said attachment being so located on said door that the distance of 60 said member from said door closer is a minimum when the door is closed and is a maximum when the door is open, the said maximum distance being in excess of twice the said minimum distance.

8. In a connection for a door and a door closer, an arm having an inner end portion attached to the door closer, a member constrained to move along said arm, a support for said member having an attachment on said door, said attachment being so located on said door that the distance of 70 said member from said door closer is a minimum when the door is closed and that said distance is a maximum when the said door is open, the said maximum distance being approximately three 75

times the said minimum distance, and said arm having a stop to prevent the said member from passing beyond said maximum distance.

9. In a connection for a door and a door closer, an arm having an inner end portion attached to a shaft of a door closer, a member constrained to move along said arm, a support for said member having an attachment on said door, said

attachment being so located on said door relative to said door closer that the distance from the shaft of the door closer to the aforesaid member when the door is fully opened is in excess of three times the distance from the shaft to the said member when the door is closed. 5
